UNITED STATES PATENT OFFICE.

WILLIAM CRIGHTON, OF FALL RIVER, MASSACHUSETTS.

IMPROVED BLIND AND SHUTTER FASTENER.

Specification forming part of Letters Patent No. 42,929, dated May 31, 1864.

To all whom it may concern:

Be it known that I, WILLIAM CRIGHTON, of Fall River, in the county of Bristol and State of Massachusetts, have invented a new and Improved Window Blind and Shutter Fastening; and I do hereby declare that the following is a full, clear, and exact description of the same, reference being had to the accompanying drawings, making a part of this specification, in which—

Figure 1 is an outer view of a window-blind with my improvement applied to it; Fig. 2, a vertical section of the same, taken in the line *x x*, Fig. 1.

Similar letters of reference indicate corresponding parts in the two figures.

This invention consists in the employment or use of two plates of precisely similar form fitted on a pin in a socket, which is inserted in the lower edge of a blind or shutter and arranged in such a manner that the blind or shutter will become fastened when thrown open or when closed, and the fastening, when the blind or shutter is closed, not admitting of being unfastened from the outer side of the latter, but from the inner side only, but admitting of being unfastened when the blind or shutter is secured in an open state. By this arrangement, a very simple, economical, and durable blind and shutter fastening is obtained, all springs being avoided, as well as other parts liable to get out of repair or become deranged by use.

To enable those skilled in the art to fully understand and construct my invention, I will proceed to describe it.

A represents a window-blind, which may be constructed and hung in the usual way to the window.

B is a metal socket formed of a base-plate, *a*, and the two upright sides *b b*, the latter being fitted in a square recess, *c*, made in the lower edge of the blind *A*, the base-plate *a* being screwed to the bottom of the blind. The base-plate *a* has a vertical pin, *b'*, fitted in it, said pin extending up into the blind above the recess *c*, as shown in Fig. 2.

C C' are two metal plates, each of which is perforated with a hole, *d*, near its inner end. These plates are fitted loosely on the pin *b'*, the latter passing through the holes *d*. The inner ends of the plates *C C'* overlap, as shown clearly in Fig. 2, and the plate *C* projects from the inner side of the blind upon the sill *D* of the window when the blind is

closed, the plate *C'* projecting from the opposite side of the blind. The plate *C'* is above and rests upon the plate *C*, as shown in Fig. 2, and both plates *C C'* have a hole, *e*, made in them near their outer ends, the hole of the plate *C* enabling said plate to catch on a vertical pin, *f*, in the sill *D* of the window when the blind closes, and the hole in the plate *C'* admitting of said plate catching on a hook, *g*, in the side of the building as the blind reaches a fully-open position. The plates *C C'* drop on this pin and hook by their own gravity.

From the above description it will be seen that no springs of any kind are required; and it will further be seen that when the blind is in a closed state that it cannot be unfastened from its outer side, as the plate *C'*, which projects from the outer side of the blind, is above plate *C*, and is incapable of raising the latter off from its pin *f*; but when the blind is fastened in an open state the plate *C'* may be readily lifted off from its hook *g* by actuating plate *C*, as the inner end of the latter is underneath the plate *C'*. Thus the device forms a lock to prevent the blind from being illegitimately opened from its outer side when closed, and at the same time admits of the blind being readily unfastened from the inner side when closed, and also readily unfastened when secured in an open state.

I am aware that numerous examples exist of shutter-fastenings which admit of being released from the opposite side when the shutter is open, and not when it is closed; but I know of no previous instance in which a pair of plates of simple and similar form have been made to operate in this way without the assistance of a spring.

The advantages of my invention are, its simplicity and cheapness, combined with full efficiency.

Having thus described my invention, what I claim as new, and desire to secure by Letters Patent, is—

The combination of the two similarly-formed plates *C C'* with apertures *d e*, the pins *b' f*, and *g'*, and the socket *a b c*, all constructed, arranged, and operating in the manner and for the purposes herein specified.

WILLIAM CRIGHTON.
